ONE-PIECE VACUUM CAP

Filed Aug. 7, 1928

Inventor
Charles Hammer
by his Attorney

UNITED STATES PATENT OFFICE

CHARLES HAMMER, OF HOLLIS COURT BOULEVARD, NEW YORK, ASSIGNOR, BY MESNE ASSIGNMENTS, TO ANCHOR CAP & CLOSURE CORPORATION, OF LONG ISLAND CITY, NEW YORK, A CORPORATION OF NEW YORK

ONE PIECE VACUUM CAP

Application filed August 7, 1928. Serial No. 297,976.

The present invention relates to closures or caps for containers, such as glass containers, and more particularly to caps adapted to be used when such containers are sealed 5 hot or with a partial vacuum therein.

Heretofore where caps were provided with a composition rubber flowed thereinto for effecting the sealing of the cap onto the container, there has been a considerable waste of 10 this material, in view of the fact that the cap top had a diameter equal to the skirt and consequently projected beyond the sealing surface of the container a sufficient distance to permit the skirt to overlap the threads 15 which usually extend out from the neck of the container about seventy-nine thousandths (79/1000) of an inch. Consequently, when the composition was flowed into the cap, it also filled this waste space between the outer 20 wall of the neck and the skirt and had no effect in the sealing of the container, and as this compo-material is expensive, it consequently required considerably more compo 25 than is necessary to properly seal the container, so that in the use of millions of caps per day, this waste of compo amounts to considerable. The present invention aims not only to provide a cap which will reduce to a minimum the amount of compo necessary to 30 properly seal the cap, but also to provide a cap which needs only a slit for the purpose of releasing the vacuum and which slit is so located that the instrument to be projected therethrough will be guided between the 35 under face of the compo and the top sealing face of the container, thereby reducing to a minimum liability of injuring the compo-material so that the cap may be readily reused.

40 Caps have heretofore been provided with openings or slots for this purpose, but these have been of considerable size, which necessarily weakened the skirt and so materially interfered with the holding efficiency of the 45 cap and the effective sealing of the container; but by the present improvement I am enabled to use a mere slit in the cap, which does not have the disadvantages referred to.

An object of the present invention is to 50 provide an improved vacuum cap constructed

to minimize the sealing composition required therefor.

Another object of the invention is to minimize the amount of composition required in a rotary or screw cap, thereby reducing the 55 cost thereof.

Another object of the invention is to provide a very small slit in a closure cap for releasing the vacuum to facilitate the removal of the cap.

Another object of the invention is to provide a slit in the skirt of a cap which does not materially weaken the cap or interfere with its holding efficiency.

Other and further objects of the invention 65 will be obvious upon an understanding of the illustrative embodiment about to be described or will be indicated in the appended claims, and various advantages not referred to herein will occur to one skilled in the art 70 upon employment of the invention in practice.

A preferred embodiment of the invention has been chosen for purposes of illustration and description and is shown in the accompanying drawings, forming a part of the 75 specification, wherein,

Figure 1 is a side view, partly in section, of this improved cap applied to a container;

Fig. 2 is an under side view of the cap;

Fig. 3 is a detail sectional view of the cap applied to a container; and

Fig. 4 is a perspective view of a portion of the cap, the several views being enlarged.

Similar characters of reference indicate 85 corresponding parts in the several views.

Before explaining in detail the present improvement and mode of operation thereof, I desire to have it understood that the invention is not limited to the details of construction and arrangement of parts which are illustrated in the accompanying drawings, since the invention is capable of other embodiments, and that the phraseology which I employ is for the purpose of description 90 and not of limitation.

The shouldered container 2, usually of glass, is provided with suitable projections or divided threads 3 for the reception of the cap 4, which comprises a top 5 and a depend- 100

ing skirt 6, the latter having a beaded or curled strengthening edge 7 and suitable strengthening corrugations 8, both of which have their useful purposes in a cap of this kind. The bead 7 of the cap is provided, in the present instance, with a plurality of locking lugs 9 of crescent shape for engagement with the threads 3 of the container. Ordinarily the top 5 of the cap extends outwardly to the skirt, having substantially the same diameter as the skirt, thus leaving a considerable waste space, as *w* in Fig. 3, between the outer side wall *b* of the container and the inner wall *c* of the skirt, into which the sealing composition flows—but which serves no useful purpose, since the seal of the cap is only as wide as the thickness of the container wall at the mouth *d* of the container, and consequently there is a considerable loss of compo, which, as hereinbefore stated, is expensive.

For the purpose of reducing the amount of compo required and so avoiding the waste thereof, the top of the cap is joined to the skirt by an annular step 10, which thus reduces the diameter of the top to practically or substantially the over-all diameter of the container mouth, this step being formed by a depending or rim portion 11 of the top and a horizontal or flat inturned flange portion 12 of the skirt joined at right angles to each other, the juncture point of these parts being located somewhat above the top of the container and the under sealing surface of the compo. This depending annular rim portion 11 of the top or riser of the annular step, together with an inwardly-inclined portion 13 of the top, forms an annular recess 14 of about the thickness of the container wall into which the composition is placed, it being flowed thereinto so that this outer rim wall 11 not only protects the composition from injury, but limits the amount that is flowed into the cap and reduces the amount required, since it is only where this composition engages the top of the container that it is sealed.

For the purpose of releasing the vacuum, the skirt is provided with a mere slit 15; but, as it is essential that this slit be located at the under sealing face of the compo and top face of the container, the inturned flange or horizontal step portion 12 of the skirt is depressed, as at 16, below the horizontal step thereby forming, as it were, a step within a step and providing a closed wall casing 17 (Fig. 2) on the inside of the cap which is provided with a slit 15 for the insertion of a suitable small sharp instrument for releasing the vacuum, this slit 15 being located at the juncture point of the horizontal portion of the small or recessed step and the depending rim portion of the top, so that it is in line with the top face of the container and the under face of the sealing compo. The horizontal portion of the small step thus acts

as a rest or guide for the insertion of a sharp instrument, thereby insuring the proper insertion of the instrument exactly between the top face of the container and the under face of the compo and so preventing injury to the 70 compo and permitting the cap to be reused. This improved structure enables the cap to be provided with a mere slit instead of an opening or slot of considerable size, so that consequently the skirt of the cap is not weakened, 75 while the location and construction of this slit also insure the proper use of the releasing instrumentality so as not to injure the compo so the cap can be readily reused. The improved construction also reduces to a minimum 80 the amount of compo necessary to properly seal the cap, so that the advantages thus obtained are of considerable importance in the manufacture and use of millions of caps per day.

From the foregoing it will be observed that I have provided a one-piece vacuum, lug-formed, rotary and reusable cap into which the compo may be readily flowed, 85 while the amount of compo required is materially reduced, thus making for a more economical cap for efficiently sealing the container, while at the same time I have provided a cap that can be readily released without injury to the compo and without any weakening 90 of the skirt of the cap and which can be readily released quickly and efficiently by the ordinary user.

As various changes may be made in the form, arrangement, and construction of the 100 parts of the preferred embodiment illustrated without departing from the spirit of the invention, it is to be understood that all matter herein is to be interpreted as illustrative and not in a limiting sense.

Having thus explained the nature of my said invention and described a way of constructing and using the same, although without attempting to set forth all of the forms in which it may be made, or all of the modes 105 of its use I claim:

1. A rotary vacuum sealed cap comprising a top provided with a depending rim portion forming an annular recess for the reception of a sealing material, and a skirt having an inwardly extending flange portion joined to said depending rim portion to form an annular step, whereby the top of the cap is of materially less diameter than the skirt portion 115 thereof resulting in a material saving in the sealing material, said annular step having a depressed portion provided with a slit 120 to facilitate the breaking of the vacuum within the container.

2. A rotary vacuum sealed cap comprising a top provided with a depending rim portion forming an annular recess for the reception of a sealing material, and a skirt having an inwardly extending flange portion joined to 125 said depending rim portion to form an annu-

lar step, whereby the top of the cap is of materially less diameter than the skirt portion thereof resulting in a material saving in the sealing material, said annular step having a depressed portion provided with a slit through the juncture of said depressed portion and rim.

3. A rotary vacuum sealed cap comprising a top provided with a depending rim portion forming an annular recess for the reception of a sealing material, and a skirt having an inwardly extending flange portion joined to said depending rim portion to form an annular step, whereby the top of the cap is of materially less diameter than the skirt portion thereof resulting in a material saving in the sealing material, said flange portion of the skirt having a depressed portion forming a casing on the inside of the cap provided with a slit.

4. A closure cap comprising a top and a skirt, said top having an annular depending rim and said skirt having an annular in-turned substantially flat flange joined together within the skirt whereby the top has less diameter than the skirt for the reception of a sealing material within the rim of the top, said cap having a slit in the depending rim of the cap and means adjacent thereto for guiding a releasing instrumentality.

5. A closure cap comprising a top and a skirt, said top having an annular depending rim and said skirt having an annular in-turned flange joined together within the skirt whereby the top has less diameter than the skirt for the reception of a sealing material within the rim of the top, said cap having a slit in the depending rim of the cap located below the inturned flange of the skirt and in substantial alignment with the top of the container.

6. A closure cap comprising a top and a skirt provided with locking lugs, said top having an annular depending rim and said skirt having an annular inturned flange joined together within the skirt whereby the top has less diameter than the skirt for the reception of a sealing material within the rim of the top, said cap having a slit in the depending rim of the cap located below the inturned flange of the skirt and in substantial alignment with the top of the container.

7. A closure cap comprising a top and a skirt provided with locking lugs and reinforcing corrugations, said top having an annular depending rim and said skirt having an annular inturned flange joined together within the skirt whereby the top has less diameter than the skirt for the reception of a sealing material within the rim of the top, said cap having a slit in the depending rim of the cap located below the inturned flange of the skirt and in substantial alignment with the top of the container.

8. A closure cap comprising a top and a

skirt, said top having an annular depending rim and said skirt having an annular in-turned flange joined together within the skirt whereby the top has less diameter than the skirt for the reception of a sealing material within the rim of the top, said rim and flange forming an annular step having a depressed recessed portion provided with an opening at the juncture thereof with the depending rim for the insertion of a releasing instrumentality.

9. A closure cap comprising a top and a skirt, said top having an annular depending rim and said skirt having an annular in-turned flange joined together within the skirt whereby the top has less diameter than the skirt for the reception of a sealing material within the rim of the top, said rim and flange forming an annular step having a depressed recessed portion forming a casing on the interior of the cap, said cap having an opening at the lower portion of said depending rim for the reception of a releasing instrumentality.

10. A closure cap comprising a top and a skirt, said top having an annular depending rim and said skirt having an annular in-turned flange joined together within the skirt whereby the top has less diameter than the skirt for the reception of a sealing material within the rim of the top, said rim and flange forming an annular step having a depressed recessed portion forming a casing on the interior of the cap, said cap having an opening for the reception of a releasing instrumentality, said opening being located at the lower corner of said casing whereby it is in line with the under sealing face of the sealing material and the top face of the container.

11. A closure cap comprising a top and a skirt joined together below the top of the cap and within the skirt by an annular step whereby the top of the cap has a diameter substantially coinciding with the overall diameter of the container mouth, said annular step having a depressed recessed portion forming a step within the annular step, said depressed recessed portion having at the inner corner thereof a vacuum releasing instrumentality opening.

12. A closure for containers comprising a top having a depending rim portion forming an annular recess for the reception of a sealing material, a skirt joined to said rim portion by an inturned horizontal flange, the juncture point of which is located above the top of the container and the under side of the sealing face of the cap thereby forming an annular step whereby the top of the cap has less diameter than the diameter of the skirt, said inturned flange of the skirt having a depressed recessed portion, the bottom wall of which is located substantially in line with the under sealing face of the container, said

cap having a slit substantially in line with the bottom wall of said depressed portion.

13. As an article of manufacture, a rotary vacuum sealing cap comprising a top provided with a depending rim portion terminating substantially at the top edge of the container when the cap is in sealing position and forming an annular recess for the reception of the sealing material in position to engage the top of the container, an annular ring of sealing material abutting said downwardly depending portion, and a skirt having an inwardly extending flange portion substantially at the level of the top of the container joined to said depending rim portion and perpendicular thereto to form a substantially resilient annular step, adapted to increase the effectiveness of the seal whereby the top of the cap is of materially less diameter than the skirt portion thereof thereby resulting in a material saving in the width of the sealing material.

14. A rotary vacuum sealing cap comprising a top provided with a depending rim portion terminating substantially at the level of the top of the container when the cap is in sealing position and forming an annular recess for the reception of a relatively thin sealing material in position to engage the top of the container, an annular ring of sealing material abutting said downwardly depending portion, and a skirt having an inwardly extending flange portion joined to said depending rim portion to form an annular step, whereby the top of the cap is of materially less diameter than the skirt portion thereof resulting in a material saving both in the width and thickness of the sealing material, said skirt having a slit therein adjacent said rim portion of the top adapted to facilitate the breaking of the vacuum within the container.

15. A closure cap comprising a top and a skirt, said top having an annular depending rim terminating substantially at the level of the top of the container when the cap is in sealed position, and said skirt having an annular inturned substantially flat flange joining the skirt and rim, and perpendicular thereto, to increase the effectiveness of the seal, whereby the top has less diameter than the skirt for the reception of sealing material within the rim of the top and in position to engage the top of the container, thereby resulting in a material saving in the width of the sealing material.

16. As an article of manufacture, a rotary sealing cap having a cover portion and a depending skirt, and having a downwardly extending part the diameter of which is smaller than the diameter of the skirt of the cap to form an annular step for the sealing material and to decrease the width thereof and to effect a saving in sealing material, and a ring of sealing material adapted to be flowed into

the cap abutting said downwardly extending part adapted to form a seal on the top edge of a container, said downwardly extending part having a slit therein to facilitate the removal of the cap from a container.

17. As an article of manufacture, a rotary sealing cap having a top portion and a depending skirt, and having a downwardly extending part the diameter of which is smaller than the diameter of the skirt of the cap to form an abutment for the sealing material adapted to be flowed into the cap and to decrease the width thereof, the length of said downwardly extending part being substantially equal to the thickness of the sealing material, and a ring of sealing material abutting said downwardly extending part and fitting against the top portion of the cap to engage and form a top edge seal on the container.

18. As an article of manufacture, a rotary sealing cap having a cover portion and a depending skirt, and having a downwardly extending part the diameter of which is smaller than the diameter of the skirt of the cap to form an abutment for the sealing material and to decrease the width thereof, the length of said downwardly extending part being substantially equal to the thickness of the sealing material, said cap having an aperture at the bottom of said downwardly extending part to facilitate breaking the vacuum.

Signed at Brooklyn, N. Y., this 31st day of July, 1928.

CHARLES HAMMER.
